UNITED STATES PATENT OFFICE.

ALBERT B. DICK, OF LAKE FOREST, ILLINOIS, ASSIGNOR TO A. B. DICK COMPANY, OF CHICAGO, ILLINOIS, A CORPORATION OF ILLINOIS.

DUPLICATING APPARATUS.

No. 903,457.

Specification of Letters Patent.

Patented Nov. 10, 1908.

Application filed September 24, 1907. Serial No. 394,902.

To all whom it may concern:

Be it known that I, ALBERT B. DICK, a citizen of the United States, residing at Lake Forest, in the county of Lake and State of Illinois, have invented a certain new and useful Improvement in Duplicating Apparatus, of which the following is a specification.

This invention relates to duplicating apparatus and refers more particularly to the combination of sheet-feeding devices and duplicating mechanism forming an apparatus which is capable of efficient and reliable operation, which may be run at comparatively high speed, and with which superior results are obtained.

The invention may be employed in connection with duplicating mechanism of various types, as, for instance, those printing from type-forms which either reciprocate or rotate, but it is particularly well adapted for use with stencil-duplicating machines employing a drum having the stencil secured thereon and a pressure-roller coacting therewith.

In all duplicating machines, and especially in stencil-duplicators, arranged to deposit the sheets, after they have been imprinted upon, one on top of another, ink on one sheet is apt to be transferred to the back of the overlying sheet and the impression on the under sheet is apt to become blurred. For this reason, the expedient of interleaving sheets between the impression-sheets has been employed, this being done either by hand or by depositing an interleaving sheet on top of each impression-sheet after the latter reaches the delivery-tray.

In accordance with my invention, two sheets, one an interleaving sheet and the other an impression-sheet, are fed simultaneously to the duplicating mechanism, one on top of the other, and the impression-sheet is imprinted upon and the two sheets fed out of the machine to the delivery-tray simultaneously. Two sheet-feeding devices are employed, one for the interleaving sheets and the other for the impression-sheets, and these operate in unison with each other and with the printing devices, so that an impression-sheet and an interleaving sheet are fed together to the printing devices for each operation of the latter. In this way, there is an interleaving sheet directly under each

impression-sheet in the delivery-tray, and blurring of the impressions and soiling the backs of the impression-sheets are effectually prevented.

The preferred embodiment of the invention is illustrated in the accompanying drawings, in which

Figure 1 is a plan view of the machine with certain of the parts broken away; Fig. 2 is a central section thereof; and Figs. 3 and 4 are detail views hereinafter referred to.

Referring to these drawings, A indicates the base of the machine, upon which is supported a suitable frame, comprising, usually, side-members B, between which is pivoted upon the stub-shafts c the stencil-carrying drum C upon the periphery of which the stencil-sheet is stretched. Directly underlying the stencil-carrying drum and operated by peripheral contact therewith or with the intervening impression-sheet, is the pressure-roller D, here shown as journaled at d upon arms E hinged at e to the side-members of the frame. Springs F tend to exert upward pressure upon the pressure-roller. Cams f mounted upon a shaft f', actuated by a suitable hand-piece outside the frame of the machine, serve to move the pressure-roller D to operative or inoperative position, the latter of which positions is illustrated in Fig. 2.

The stencil-carrying drum C is rotated in any suitable manner, as, for instance, by a handle connected or geared to one of the stub-shafts c. The stub-shaft c on the opposite side of the machine carries a gear c' which forms one of a train of gears c² connecting the stencil-carrying drum to a gear c³ mounted on a suitable stub-shaft on one of the frames B. Each of the gears of this train is mounted for rotation on a stub-shaft secured on the frame B, as illustrated in Fig. 1. Secured to the gear c³, are a locking-plate c⁴ and a mutilated gear- c⁵. Mounted for rotation in suitable bearings formed in the frames B, is a shaft g having a stop-roll G loosely mounted thereon and connected thereto by a clutch g' arranged to permit rotation of roll G in one direction free of shaft g but connect the shaft in driving relation to the roll when the former is positively driven. One end of the shaft g extends through the bearing in the frame B

and has a pinion g^2 fixed thereto meshing with the gear c^3 . Loose on the shaft g are a plate g^3 having a tooth adapted to coact with a notch in the locking-plate c^4 , and a pinion g^4 adapted to mesh with the mutilated gear c^3 , the disk g^5 and pinion g^4 being relatively immovable. The pinion g^4 meshes with an idler-pinion h , which meshes with a pinion h' secured upon one end of a shaft h^2 which is mounted for rotation in bearings formed in the frames B. Shaft h^2 carries a sheet-feeding roll H, which is loose on the shaft but adapted to be connected thereto by a clutch h^3 similar to the clutch g^1 .

15 The roll G has a shallow peripheral groove cut therein. Directly underlying this roll is a bar I extending between the side-frames and having a vertical opening therein to receive a pin i , the lower end of which is threaded and enters a threaded opening in a gear i' mounted for rotation between the bar I and a support depending therefrom. On the upper end of the pin i is a block i^2 carrying a stop-plate i^3 . Suitable means are provided for rotating the gear i' so as to raise or lower the pin i , block i^2 and stop-plate i^3 , and thus cause the end of the stop i^3 to enter more or less into the groove in the roll G.

20 J indicates a tray adapted to support a pile of interleaving sheets. This tray is formed of sheet-metal and is pivotally mounted upon studs j extending inwardly from the ends of the frames B. At its outer 25 end the tray J has a weight j' adjustably mounted upon the under side thereof. This weight serves to rock the tray on its pivot in the direction to raise the opposite end of the tray and thus press the pile of sheets upwardly into contact with the surface of the sheet-feeding roll H. The provision of the 30 adjustment of the weight j' toward and away from the pivots of the tray permits of adjusting the pressure of the sheet pile 35 40 45 against the sheet-feeding roll.

K and K' indicate sheet-forwarding rollers, on which a plurality of belts k are adapted to run. The roller K is mounted on shaft k' , one end of which is extended 50 through its bearing in the side-frame B and carries a pinion k^2 meshing with an idler-pinion k^3 which meshes with the gear c^3 (Fig. 3). A sheet-forwarding roller k^4 is mounted for rotation in bearings formed in 55 the ends of arms k^5 which are pivotally mounted on stub-shafts k^6 extending inwardly from the frames B, and springs k^7 are provided on these stub-shafts and arranged to actuate the arms k^5 to press the 60 roller k^4 downwardly upon the surface of the belts k running on the forwarding-roller K. Movable guides k^8 are provided for co-acting with the lateral edges of the sheets as 65 they are forwarded by the belts, these guides being arranged to shift the end belts k

toward and away from each other. The forwarding-roller K' turns freely in its bearings, actuated by the belts k .

Turning now to the sheet-feeding apparatus for the impression-sheets, L indicates a tray for the pile of impression-sheets, having adjustable guides l at its sides. This tray is of sheet-metal and at its forward edge has downwardly turned ears l' with openings therethrough adapted to receive pins carried by the side-frames B. The opposite end of the tray rests upon stationary pins l^2 extending inwardly from the frames B. The forward edge of the tray L lies close to the forwarding-roller K'; beyond this roller and between it and the drum C, is a plate l^3 having a slot cut therein.

M and N indicate sheet-feeding rollers which are operated intermittently to feed forward to the drum C an impression-sheet

85 passed thereto from the tray L. These rollers are preferably of sectional form, one or both of them being of rubber. I also employ, preferably, a sheet-guide R, here shown as secured to the frames B and arranged obliquely to form a wedge-shaped opening into which the sheets may be passed to the rollers M, N. This sheet-guide is here shown as provided with fingers r coextensive in size 90 with the sections of the feed-roller M and terminating immediately below or slightly rearward of those sections. The roller N operates in the slot formed in the plate l^3 , its upper surface being flush with or slightly above the surface of the plate. The roller M 100 is loose on its shaft, but is adapted to be connected thereto by a clutch m similar to the clutch g^1 . This roller carries a pinion m^2 which meshes with a pinion n on the shaft of the lower roller N. At the end of the shaft 105 m' adjacent clutch m , is secured a pinion m^3 , which meshes with a pinion o mounted for rotation on a stub-shaft extending inwardly from the frame B. Secured to this pinion is a roller o' , the surface of which is covered 110 with a yielding material, such as leather, felt or rubber. The roller o' is adapted to be actuated by a portion of the duplicating mechanism, so that the sheet-feeding rollers M and N will operate in unison with this 115 mechanism. For this purpose, I have shown the feed-roll-actuating device as carried by the drum C. This device comprises a sector O pivoted on one of the stub-shafts c and having a serrated edge (see Fig. 4) 120 adapted to coact with the surface of the roller o' . This sector O is provided with an elongated slot o^2 , through which extends a screw o^3 , the end of which is received in a suitably threaded orifice in the adjacent head 125 of the drum. Suitable stripping devices are provided for preventing the sheets from being carried around with the drum C, but since these form no part of my present invention they will not be described in detail. 130

After the impression sheets have been imprinted upon and the two sheets fed simultaneously from the drum, the sheets fall together in a suitable delivery-tray, indicated 5 at P.

In the operation of the machine, a pile of interleaving sheets is placed upon the tray J and moved forwardly thereon between the side-guides carried by the tray until the forward edge of the pile abuts against the stop-plate i^2 . The weight j' is then adjusted so that the pile of sheets at its forward edge is pressed upwardly against the under surface of the sheet-separating roll H with the desired degree of pressure. A pile of impression-sheets is then placed upon the tray L. The stencil having been secured upon the periphery of the drum C in the usual manner, the operation of the machine is begun. 10 As the drum C rotates, the feed-rollers M and N are intermittently actuated by the coaction of the edge of sector O with the roller o' , driving the feed-rollers through the gearing o, m^3, m^2 and n . Also, the forwarding-rollers K, K' and k^4 and the belts k and the stop-roll G are continuously rotated by the gear c^3 and the sheet-separating roll H is intermittently rotated by means of the gearing c^5, g^4, h and h' . When the sheet-separating roll H 15 is rotated, the topmost sheet of the pile on the tray J is moved forwardly between the stop-plate i^2 and the stop-roll G to the forwarding-rollers K, k^4 . The position of the stop-plate i^2 relatively to the stop-roll G may be 20 delicately adjusted to preclude the passage of more than one sheet between these parts. Before the rotation of the sheet-feeding roll H is discontinued, the edge of the sheet is grasped between the forwarding-rollers K and k^4 and the sheet is forwarded by these 25 rollers and the belts k to the drum C. As this interleaving sheet is moving forwardly upon the belts k , the operator grasps the rear edge of the topmost sheet of the pile on the tray L and passes the sheet forwardly until its forward edge enters between the sheet-feeding rollers M and N. As the drum C 30 continues its rotation, the edge of the sector O engages the roller o' and operates to rotate the rollers M and N. The rotation of these rollers preferably begins just as the forward edge of the interleaving sheet reaches them and the forward edge of the impression-sheet 35 from the tray L is grasped between these rollers and fed forwardly to the drum C, together with the interleaving sheet directly underlying the impression-sheet. After the forward edges of the two sheets have passed beyond the pressure-roller D, the latter is 40 raised to operative position by the springs F and the two sheets are grasped between the pressure-roller D and the drum C, this taking place before the positive operation of the feed-rollers M and N has been discontinued, 45 due to the passage of the end of the sector O

beyond the roller o' . The impression-sheet is then imprinted upon and the two sheets fed out of the machine simultaneously in the usual manner, the feed-rollers M and N turning freely to permit this. In the delivery-tray 70 P, there is an interleaving sheet directly above each of the impression-sheets so that blurring of the impressions is prevented.

Having now described my invention, what I claim as new therein and desire to secure 75 by Letters Patent is as follows:

1. In a printing mechanism, the combination of a drum, a stencil secured to the periphery thereof, a pressure-roller adjacent to the drum, a sheet-feeding device mounted adjacent to the line of coaction of the drum and pressure-roller, two supports for sheet piles located in coöperative relation to said device and from which sheets may be fed simultaneously to said device, means for operating said sheet-feeding device intermittently in correspondence with the rotation of said drum, and means for effecting an adjustment of the time of operation of said sheet-feeding device with respect to the rotation of said drum, substantially as set forth. 80

2. In a printing mechanism, the combination of a drum, a stencil secured to the periphery thereof, a pressure-roller adjacent 95 to the drum, a sheet-feeding device mounted adjacent to the line of coaction of the drum and pressure-roller, two supports for sheet piles located in coöperative relation to said sheet-feeding device and from which sheets 100 may be fed simultaneously to said device, and a part adjustably mounted on said drum and adapted to operate said sheet-feeding device intermittently to feed said sheets between the drum and pressure-roller, substantially as set forth. 105

3. In a printing mechanism, the combination of a drum, a stencil secured to the periphery thereof, a pressure-roller adjacent to the drum, a pair of sheet-feeding rolls 110 mounted adjacent to the line of coaction of said drum and pressure-roller, two feed-boards located in coöperative relation to said rolls and from which sheets may be fed simultaneously to said rolls, and a part adjustably mounted on said drum and adapted to rotate said rolls intermittently to feed said sheets between the drum and pressure-roller, substantially as set forth. 115

4. In a printing mechanism, the combination of a drum, a stencil secured to the periphery thereof, a pressure-roller adjacent to the drum, a pair of sheet-feeding rolls mounted adjacent to the line of coaction of said drum and pressure-roller, an automatic 120 sheet-feeding device for feeding sheets successively to said rolls, a feed-board located in coöperative relation to said rolls from which sheets may be fed successively to said feed-rolls simultaneously with the sheets fed 125 130

by said device, means for rotating said drum, means for operating said device, and a part adjustably mounted on said drum and adapted to rotate said rolls intermittently to feed said sheets between the drum and pressure-roller, substantially as set forth.

5. In a printing mechanism, the combination of a drum, a stencil secured to the periphery thereof, a pressure-roller adjacent to the drum, a pair of sheet-feeding rolls mounted adjacent to the line of coaction of said drum and pressure-roller, an automatic sheet-feeding device for feeding sheets successively to said rolls, a feed-board mounted above said device with its forward edge adjacent to said feed-rolls and from which sheets may be fed successively to said feed-rolls simultaneously with the sheets fed by said device, means for operating said drum and said device, means for rotating said feed-rolls intermittently in correspondence with the rotation of said drum to feed said sheets between the drum and pressure-roller, and means for effecting an adjustment of the time of operation of said feed-rolls with respect to the rotation of said drum, substantially as set forth.

6. In a printing machine, the combination of a drum, a stencil secured to the periphery thereof, a pressure-roller adjacent to the drum, a sheet-feeding device for feeding sheets between the drum and pressure-roller, a feed-board from which sheets may be fed to said device, an automatic sheet-feeder for feeding sheets successively to said device, means for operating said device intermittently in correspondence with the rotation of said drum, and means for effecting an adjustment of the time of operation of said sheet-feeding device with respect to the rotation of said drum, substantially as set forth.

7. The combination of a printing mechanism comprising a drum, a stencil secured to the periphery thereof and a pressure-roller

adjacent to the drum, a support for a sheet pile, means for automatically feeding sheets from said pile, a pair of sheet-feeding rolls, a single means for rotating said drum and operating said sheet-feeding means, and means actuated by said drum for operating said rolls intermittently to feed sheets between the drum and said pressure-roller simultaneously with the sheets fed by said means, substantially as set forth.

8. The combination of a printing mechanism comprising a drum, a stencil secured to the periphery thereof and a pressure-roller adjacent to the drum, a support for a sheet pile, means for automatically feeding sheets from said pile, a pair of sheet-feeding rolls lying adjacent to said drum and one above and the other below the path of movement of the sheets fed by said means, means for operating said drum and said sheet-feeding means, a feed-board adjacent to said rolls from which sheets may be fed to the roller additional to the sheets fed by said automatic feeding means, and a part rotating with said drum arranged to rotate said rolls intermittently, substantially as set forth.

9. The combination of a printing mechanism comprising a drum, a stencil secured to the surface thereof and a pressure-roller adjacent to the drum, a pivoted support for a sheet pile, a separator-roll overlying the end of said support, a stop-roller adjacent to said separator-roll, a stop coacting with and adjustable toward and away from said stop-roller, and a single means for continuously rotating said drum and said stop-roller and intermittently rotating said separator-roll, substantially as set forth.

This specification signed and witnessed 85 this 21st day of September, 1907.
